[57] CLAIM

The ornamental design for a junction box, as shown and described.

DESCRIPTION

FIG. 1 is a front and upper right perspective view of a junction box showing my new design;
FIG. 2 is a front elevational view of the junction box shown on an enlarged scale, the rear elevational view thereof being identical except for the order of the letters;

FIG. 3 is a left side elevational view thereof;

FIG. 4 is a top plan view thereof; and,

FIG. 5 is a bottom plan view thereof.

FIG. 1

FIG. 2.

FIG. 4.

FIG. 3.

FIG. 5.
